UNITED STATES PATENT OFFICE.

JOHN KEYWORTH FLETCHER, OF NOTTINGHAM, ENGLAND.

DESIGN FOR LACE FABRIC.

SPECIFICATION forming part of Design No. 23,230, dated May 1, 1891.

Application filed March 22, 1894. Serial No. 504,727. Term of patent 3½ years.

To all whom it may concern:

Be it known that I, JOHN KEYWORTH FLETCHER, a citizen of England, and a resident of Nottingham, in the county of Nottingham, England, have invented a new and original Design for Lace Fabric, of which the following is a specification, reference being had to the accompanying drawing, showing a part thereof.

10 The drawing represents a piece of my newly designed lace fabric.

The leading feature of my design consists of a lace fabric provided with floral ornaments and an arched border having radially 15 projecting ovals.

15 *a*, represents a floral ornament partly in-

closed within one of the arches of an arched border *b*. This border is provided with two inner parallel rows *c*, and with a series of pointed ovals *d*, that project outwardly at substantially right angles to the inner rows. 20

What I claim is—

The design for a lace fabric substantially as shown and described.

Signed at Nottingham, in the county of Nottingham, England, this 2d day of March, A. D. 1894.

JOHN KEYWORTH FLETCHER.
